UNITED STATES PATENT OFFICE.

GEORGE BECKER, OF PROVIDENCE, RHODE ISLAND.

DESIGN FOR A JEWEL-SETTING.

SPECIFICATION forming part of Design No. 16,382, dated November 17, 1885.

Application filed September 9, 1885. Serial No. 176,636. Term of patent 7 years.

To all whom it may concern:

Be it known that I, GEORGE BECKER, of the city and county of Providence, and State of Rhode Island, have invented and produced a new and original Design for Jewel-Settings, of which the following is a full, clear, and exact description, reference being had to the accompanying drawings, forming part of this specification.

10 Figure 1 represents a perspective view of the setting. Fig. 2 represents a top plan view of the same. Fig. 3 represents a cross-section on the line X X of Fig. 2.

15 The leading feature of my design consists in the spear-heads shown in the drawings, having the raised and depressed portions, whose surfaces may be given different characters of finish for the purpose of contrasting the same, and thereby producing a novel and 20 pleasing effect in an article of jewelry.

The drawings show a cluster of six of the spear-heads or standards *s s*, borne upon the base-plate *b*. These spear-heads have the raised portions *a a* and the depressions *a' a'*, and it will be seen that by giving different 25 kinds of finish to these several surfaces presented that a varied and brilliant effect can be produced.

Having thus described my new and original design, I claim as new and desire to secure by 30 Letters Patent—

The design for a jewel-setting herein shown and described, the same consisting of a base-plate, *b*, bearing the spear-heads *s s*, having the raised parts *a a* and the depressions *a' a'*.

GEORGE BECKER.
